Samuel Boyd, of New York, N.Y.
Letters Patent No. 1217 dated April 3, 1860.

The schedule referred to in these Letters Patent and making part of the same.

Dec. 12/17

To all whom it may concern,

Be it known that I, Samuel Boyd, of the City, County and State of New York, have invented and produced a new and Original Design for Andirons, and I do hereby declare that the following is a full and exact description thereof, illustrated & shown by the accompanying drawings which form a part of these my specifications.

This consists of a rocky base, around and upon which springs foliage. This is surmounted with two figures of Cupid, one in a sitting and the other in a kneeling posture.

The Kneeling figure has wings and his left arm is turned around the shaft of an upright torch the vase and flame of which forms the upper terminal composition. The left hand supports drapery against the column of the torch while the other is placed upon the mouth and cheek of the sitting Cupid.

Between the two figures and under the left foot of the Kneeling one is another torch and flame. This leg is encircled partially by the right arm of the sitting Cupid, and the right leg of the sitting figure is partially concealed by foliage springing from the rock.

The whole composition is supported by plumage, and scroll work springing from a grotesque mask, and terminating on each side of the group in feet which form the front legs of the Andiron. The wood bar and back leg is inserted in a dovetail joint cast in the hollow or reverse of the composition. The above described figures and subordinate parts are cast in alto relief, and form the front of an Andiron of elegant and classical form.

What I claim and desire to secure by Letters Patent, is the above described and illustrated composition or design.
